UNITED STATES PATENT OFFICE.

JOHN DOUGHERTY, OF COLD SPRING, NEW YORK.

IMPROVEMENT IN MOLDING.

Specification forming part of Letters Patent No. **28,260**, dated May 15, 1860.

To all whom it may concern:

Be it known that I, JOHN DOUGHERTY, of Cold Spring, in the county of Putnam and State of New York, have invented a new and Improved Machine for Operating Templets in Loam-Molding; and I do hereby declare that the following is a full, clear, and exact description thereof, reference being had to the accompanying drawings, forming a part of this specification, in which—

Figure 1 represents a side elevation of the machine. Fig. 2 is a plan view of the same.

Similar letters of reference indicate corresponding parts in both figures.

This invention is an improvement in managing the templets that are used in loam-molding for casting large work—such, for instance, as steam-cylinders, large pipes, fly-wheels, and such molds that cannot be conveniently and accurately made in the ordinary method of molding.

The method of molding such work in loam is at present attended with many difficulties familiar to those skilled in the art, which it is the special object of my invention to remedy.

For such work as steam-cylinders or wheels of large diameter the present mode of casting them, as is well known, is by building up a mold of brick-work coated or plastered with soft loam, which is scraped for cylinders into the cylindrical form by a radius-board moved round on its axis. When the surface is thoroughly dry, it is brushed over with blackwash and again dried. A templet is now used, cut exactly to the external form of the cylinder, which is attached to the axis at the distance from the core required for the thickness of the metal. Some additional loam is thrown in to form the thickness, which is smoothed in the same careful manner as the center, after which the templet and its spindle are dismounted. The base-ring for the outer case or cope is now laid down, and this outer case is built up of bricks and loam, with an inner facing of loam worked very accurately to the turned thickness. The new work or the cope is also thoroughly dried, and afterward lifted off very carefully by means of the crane and a cross-beam with four chains. The mold is now put together in a pit sunk in the floor of the foundry, and the casting is performed in any of the well-known ways.

My invention consists in a novel arrangement of gearing, combined with the central spindle carrying the templet, for giving to said templet or templets of any description, according to the kind of work, a vertical reciprocating motion or a vertical motion combined with a circular motion, as will be hereinafter described and represented.

To enable others skilled in the art to fully understand my invention, I will proceed to describe its construction and operation.

In the drawings, A represents the truck or base of the machine, upon which is erected a hollow shaft or spindle, B, having its lower bearing in a step-block, B', on the truck A, and its upper bearing in a bracket-block, C, that projects from a horizontal frame, D, placed at a suitable height above the floor of the foundry. This hollow shaft carries on its upper end a grooved spur-wheel, E, that is acted upon by a worm-wheel, hereinafter described, for giving to it a circular motion.

G is a hollow screw-shaft that passes up centrally through the hollow shaft B and through the spur-wheel E, and carries a small bevel gear-wheel, F, on the upper end. This bevel spur-wheel F is actuated by either one or the other of the twin bevel spur-wheels H H', which give to the screw-shaft a right or a left rotary motion as one or the other is brought into gear with the wheel E. The wheels H H' are on a horizontal shaft, J, and secured to this shaft by a key-tenon, a, so that they may have a longitudinal play, and thus be brought alternately into gear with the spur-wheel E. The shaft J may be driven by hand or other convenient power.

On the end of shaft J is keyed a large spur-wheel, K, which gives motion to a similar spur-wheel, K', that has its bearings in the end of a swinging iron, b, hung from the end of shaft J. The pivot-bearing of wheel K' is guided and steadied by a slotted guide-plate, c, that is secured to the end of frame D. This wheel K' is intended to transmit motion to the endless screw or worm-wheel shaft L by acting upon a pinion-spur, L'.

On the hollow shaft or spindle B is placed templet-block, M, which is a circular flanged wheel with perforations drilled through the flanges, that receive bolts for securing the radius-bar of a templet to it. This block M is

fixed to a nut, *d*, which is placed on the screw-shaft *G* by a screw, *e*, the neck of which plays up and down the slot in the hollow shaft *B*, Fig. 1.

The entire frame-work for supporting the mechanism should be made so as to be readily taken down in order to remove the molds, the manner of doing which will be understood by any mechanie.

Now, from this description it will be understood that by attaching a templet to the block *M*, of any suitable radius, it may be operated with a reciprocating motion up and down the shaft *B* by alternately engaging the twin wheels of shaft *J* with the bevel-wheel *E* of the screw-shaft *G*, or both a reciprocating and circular motion may be given to the templet-block by bringing into gear with the wheel the worm-wheel on shaft *L*, and with this latter motion spiral castings may be made.

By combining with this machine a car-

riage that will have a horizontal movement upon which the mold is built, oval or elliptical molds may be made.

The manner of constructing the molds in loam is precisely the same as that of the present mode; but the facility of operating the templets that are secured in the block *M* is the distinguishing characteristic of my invention and improvement.

Having thus described my invention, what I claim as new, and desire to secure by Letters Patent, is—

The templet-block *M*, combined with a hollow shaft, *B*, and screw-shaft *G*, and operated substantially in the manner and for the purposes herein set forth.

JOHN DOUGHERTY.
